United States Patent Office

Des. 208,793
Patented Oct. 3, 1967

208,793

CLOCK

Charles A. McLeod, Chicago, Ill., assignor to Sunbeam Corporation, Chicago, Ill., a corporation of Illinois

Filed Aug. 8, 1966, Ser. No. 3,374

Term of patent 14 years

(Cl. D42—7)

FIG. 1 is a perspective view of a clock, showing my new design;

FIG. 2 is a cross sectional view thereof taken along the line 2—2 of FIG. 1;

FIG. 3 is a rear elevational view; and

FIG. 4 is a bottom plan view thereof.

The dominant features of the design are shown in solid lines.

I claim:

The ornamental design for a clock, as shown and described.
